UNITED STATES PATENT OFFICE

ROBERT W. PHILIPS, OF GUELPH, ONTARIO, CANADA.

WRENCH.

SPECIFICATION forming part of Letters Patent No. 366,246, dated July 12, 1887.

Application filed February 28, 1887. Serial No. 229,104. (No model.)

To all whom it may concern:

Be it known that I, ROBERT WALLACE PHILIPS, of the city of Guelph, in the county of Wellington, in the Province of Ontario, 5 Canada, steam - fitter, have invented certain new and useful Improvements in Wrenches, of which the following is a specification.

The object of the invention is to design a simple self-adjusting pipe-wrench capable of 10 being used for various sizes of pipes; and it consists in the peculiar combinations and the novel construction, arrangement, and adaptation of parts, all substantially as hereinafter specified.

15 The drawing represents a perspective view of a monkey-wrench constructed in accordance with my invention.

A represents a metal bar, and C a jaw, formed with ratchet-teeth *d* and *e*, respectively, the 20 teeth *e* being set so as to point toward the handle end of the bar A, while the teeth *d* point in the opposite direction. The jaw and bar are pivotally connected together by means of the links B.

The sleeves D are fitted one onto the bar A 25 and the other onto the jaw C, and lugs *f* are formed on these sleeves to receive the pivots *a* and *b*. The sleeve D on the bar I make adjustable, holding it in place by the set-screw E. In this manner I am enabled to adjust the 30 jaw C nearer to or farther from the end of the bar A, as may be necessary, in order to make the end of the jaw C even with the end of the bar A.

What I claim as my invention is—

The combination, with the bar A and jaw C, of the sleeves D on said bar and jaw, respectively, lugs *f*, formed on said sleeves, and the links B, pivoted at their ends in said lugs, substantially as described.

Toronto, February 9, 1887.

35

ROBERT W. PHILIPS.

In presence of—

CHARLES C. BALDWIN,
FRANK X. McGEE.
